UNITED STATES PATENT OFFICE

2,600,250

TAKEDOWN METAL BOW HANDLE

Harry F. Lake and Clarence W. Grimes, Pontiac,
Mich.; said Lake assignor to said Grimes

Application July 26, 1947, Serial No. 763,928

1 Claim. (Cl. 124—24)

1

The present invention relates to a bow used in the practice of archery and more particularly to a metal bow which may be taken down for easy transportation.

Bows used in the practice of archery and in hunting vary in length from five to six feet and require from eighteen to eighty pounds of pull to properly discharge an arrow. A novice begins by practicing with a bow requiring about a 30-40 pound pull and progresses to a 50-50 pound pull bow as his strength and skill increase. Bows have been commonly made of wood, such as yew, osage orange, lemon wood and lance wood. The bows are usually made in one-piece or of continuous wooden laminae and due to their length, are awkward to handle when not in use. Bows made of wood are hand-made and consequently expensive. Wooden bows are also sensitive to heat and moisture, and the performance of a given bow may vary with the weather. Due to the construction of wooden bows a broken limb cannot be replaced, and the entire bow must be discarded.

Bows have been made of separate pieces of wood connected by metallic sleeves, the construction being similar to that of a fishing rod. The wooden portions of the bow are subject to all the faults of the wooden bow. Also, it has been difficult to obtain an even distribution of force along the limbs of such bows when under tension. Consequently, these jointed bows are not so accurate as wooden bows and have not been generally accepted.

In accordance with the present invention we provide a metal bow which may be taken down into three units for transportation. The bow of the present invention is less expensive and more accurate than the conventional wooden bow. The bow as herein provided is constructed of aluminum or an aluminum alloy, an aluminum-magnesium alloy, or other light alloy. The alloy may be anodized or otherwise treated. A bow construction of such an alloy will be unaffected by moisture or varying weather conditions. The metallic construction of the bow eliminates much of the expensive hand-work necessary in the preparation of conventional wooden bows. If one of the limbs of the bow should break the user may replace it with a new limb retaining the rest of the bow. Also a beginner may purchase one bow and merely replace the limbs with limbs requiring a greater amount of pull as his skill and strength increase. The bow is equipped with a sighting device to aid in obtaining accuracy. The bow construction permits the discharge of

2

the arrow from a point closer to the center of the bow than with the conventional type of bow. In the conventional type of bow construction the longitudinal axis of the arrow is actually at a slight angle to the path of the string as it is released. The archer must compensate for the difference in direction between the line of flight of the arrow and the path of the released bow string. In the use of the present bow the arrow is so positioned on the bow that the angle between the line of flight of the arrow and the path of the released bow string is diminished, thus increasing the accuracy of the bow.

The bow of the present invention comprises two limbs detachably mounted to an intermediate handle portion. Each of the limbs is attached to the handle by means of a pair of screws extending through the handle and the limbs. When the limbs are detached from the handle, the longest portion of the bow is approximately 28" long, or less than one-half the length of a comparable wooden bow.

The handle of the bow comprises a central grip portion, a sighting device, and a recess into which the arrow fits when the bow string is drawn. The grip portion of the handle consists of a hollow casting of a light metal or alloy as above described shaped to comfortably fit the hand when the bow is gripped by the archer. The grip may be wrapped with a non-metallic material such as leather, cloth, etc. The hollow portion of the handle lessens the weight of the bow and improves the balance of the bow. The hollow portion of the grip may be filled with a light non-metallic substance, such as cork, or it may be left empty as the archer desires. The sighting device used in aiming the bow consists of an adjustable slide mounted on a strip of metal extending vertically from the upper portion of the handle when the bow is held in normal operating position. The adjustable slide carries a small sphere mounted on a rod, which extends horizontally from the slide. The rod may be adjusted in the slide to compensate for the wind drift of the arrow during flight. The rod may be inserted in either side of the slide to accommodate either right- or left-handed archers. The handle portion is indented along the line of flight of the arrow above the grip portion of the handle to provide clearance for the arrow. An indentation is provided on either side of the bow to accommodate right- or left-handed archers. The indentations in the handle portion of the bow are provided with projections which form a support for the arrow when it is fitted to the string. The

projections are of segmental circular shape or of any other shape which will provide a minimum area of contact with the arrow. The indented handle portion together with the projection provide a path of flight for the arrow which closely approximates the path of the released string, thus increasing the accuracy of the bow as explained above.

The limbs of the bow are formed from a light metal or alloy of substantially rectangular cross section. Each limb is tapered in width from the base, which fits into the handle portion, to the tip which is of conventional design. Each of the limbs is of the same thickness throughout its entire length. The simple and efficient design of the limbs, employing the rectangular cross section and uniform thickness as above described, allows their manufacture from inexpensive standard alloy strip with a minimum of machining and finishing. Each limb is removably attached to the handle portion of the bow by means of screws which extend through the handle portion and base of the limb. The amount of taper is proportional to the thickness of the limb in order to obtain an even distribution of stress throughout the limb. Thus the taper of a quarter inch limb is greater than the taper of a $\frac{1}{8}$ inch limb. The weight of the bow or the amount of force necessary to draw the string to the rear is proportional to the thickness and taper of the limbs. The archer may change the weight of his bow, by merely replacing the limbs with limbs of different dimensions. The limbs are interchangeable and the same handle portion may be used. Thus the novice may increase the weight of his bow at little expense.

It is, therefore, an important object of the present invention to provide an effective handle member for a metal bow which may be taken down for easy transportation.

It is another important object of the present invention to provide a weather-resistant bow comprising interchangeable limbs and handle formed of a light weight metal or alloy which bow may be taken down into its component parts to provide ease of transportation.

Other and further important objects of this invention will be apparent from the following description and appended claim.

On the drawings:

Figure 1 is a side elevational view of a bow made in accordance with this invention showing the bow assembled and strung ready for use;

Figure 2 is a front elevational view of the bow of Figure 1 showing the bow unassembled and unstrung;

Figure 3 is an enlarged broken front elevational view of the bow showing the handle portion of the bow of Figure 1;

Figure 4 is an enlarged, broken, side elevational view showing the handle portion of the bow and the method of attachment of the limbs to the handle; and

Figure 5 is a sectional view taken on the line V—V of Figure 4.

Reference numeral 10 refers generally to a bow made in accordance with this invention comprising a handle portion 11, limb portions 12 and bow string 13. The limb portions 12 are attached to the handle portion 11 by Allen screws 14 which extend through holes 15 in the laterally flared terminals of the handle portion 11 and holes 16 in the limb portions 12.

The handle portion 11 consists of grip portion 17, indented portion 18 and sight assembly 19.

The centrally located grip portion 17 consists of leather covering 20 wound spirally around the grip 17 encasing the hollow portion 21 thereof. The void 21 is elliptical in shape to conform to the generally ellipsoidal curvature of the grip portion 17 and to provide a maximum cut-out area consistent with the necessary strength. The void 21 is packed with cork to give the bow less weight and greater balance than would have been possible had the grip portion been cast as a solid member.

The handle portion 11 above the grip 17 is laterally indented to form a narrow portion 11a. The narrow portion 11a is elongated as shown in Figs. 1 and 4 to avoid weakening the handle portion 11 at this point. Elongated indentations 22 are provided on either side of the narrow portion 11a for a purpose to be described later. Semi-cylindrical projections 23 are mounted in the indentations 22 on the shoulders 24 formed by the abrupt constriction of the handle portion 11 to form the narrow portion 11a. The projections 23 carry depending protuberances 25 which fit snugly into recesses in the shoulders 24 thus rigidly mounting the projections 23 thereon. An arrow 31 fitted to the bow string 13, is held in shooting position in the indentation 22 by the side 11b of narrow portion 11a to rest on the projection 23. The purpose of the indentation 22 is to allow the discharge of the arrow 31 from a position closely approximating the center of the handle portion 11. Thus, the angle between the path of the arrow and the path of the released bow string is decreased, thereby increasing the accuracy of the bow as above-described. The arrow 31 remains in contact with the narrow portion at 11b and with the projection 23 until the arrow 31 leaves the bow 10 entirely. The surface 11b and the projection 23 steady the initial flight of the arrow and further increase the accuracy of the bow. The semi-cylindrical upper surface of the projection 23 provides adequate support for the arrow 31 without excessive friction and consequent loss of velocity. The presence of an indentation 22 and a projection 23 on either side of the narrow portion 11a makes possible the use of the bow by both right and left-handed archers.

The sighting device 19 comprises an upright metal member 26 rigidly attached to the handle portion 11 and extending from the handle portion parallel to and in spaced relation with the upper limb 12 when the bow is held in normal operating position. The metal member 26 carries an adjustable slide 27 which is equipped with a small sphere 28 mounted on a rod 29. The rod 29 extends laterally past the edge of the limb so that the sphere 28 is visible to the archer. The slide 27 is adjustably attached to the metal strip 26 so that it may be moved along the strip 26 to compensate for range differences. The slide 27 may be calibrated by the individual archer so that he may obtain greater accuracy in the use of the bow. The rod 29 may be moved in the slide 27 to compensate for wind drift. The rod 29 is removable from the slide 27 for insertion from the other side of the slide 27. In this way the sphere 28 may be positioned above an arrow inserted on either side of the narrow portion 11a, thus adapting the bow for the use by either right- or left-handed persons with the same degree of accuracy for both.

Each of the limb portions 12 of the bow 10 is tapered in width from the base portion which fits into the handle portion 11 to the tip 30 to obtain the proper distribution of stress through-

out the entire length of the limb. As hereinbefore described the base portion of each of the limbs 12 is provided with holes 16 drilled therein to receive screws 14 which removably attach the limb 12 in endwise opening slots in the handle portion 11. The tips 30 are notched in the conventional manner to receive the bow string 13. The tip 30 has a reverse curvature which causes the bow string 13 to lie along a portion of the limb 12. This contact between the bow string 13 and the limb 12 serves to dampen the vibration of the bow string 13 and to decrease the noise made by the sudden release of the bow string 13. This reduction of noise is very useful where the bow of the present invention is to be used for hunting purposes. Each of limbs 12 of the bow 10 is substantially rectangular in cross section and of substantially the same thickness throughout its entire length. The weight, or the amount of pull necessary to properly discharge an arrow from the bow, is determined by the thickness and taper of the limb portion 12. The taper of the limb is proportional to the thickness of the limb, the variation of the taper being necessary to obtain an equal stress throughout the entire length of the limb. The bow 10 may be taken apart for transportation, storage or replacement of a broken limb by simply removing the screws 14 and lifting the limbs 12 from the handle portion 11.

Thus it may be readily seen that we have provided a bow having interchangeable limbs which may be taken down into its component parts when not in actual use. The bow of this invention is more accurate, more economical, and lighter in weight than wooden bows of conventional design.

It will, of course, be understood that various details of construction may be varied through a wide range without departing from the principles of this invention, and it is, therefore, not the purpose to limit the patent granted hereon otherwise than necessitated by the scope of the appended claim.

That which we claim is:

In a symmetrical take down bow for right and left handed use, an integral handle member comprising a handgrip of generally ellipsoidal curvature for anatomic conformity to a gripping hand, a laterally flared terminal portion extending endwise of one end of said handgrip and having a limb receiving slot opening endwise of said handle member, allochiral shoulder portions flared laterally of the other end of said handgrip, a narrow portion extending endwise centrally from said shoulder portions and having elongated lateral surfaces, projections carried by each of said shoulder portions in extended laterally spaced relation to said elongated lateral surfaces, said projections each having a semi-cylindrical upper surface to serve with the adjacent elongated surface as an arrow guideway, and a second terminal portion extending endwise from and flared laterally of said narrow portion in confronting relation to said shoulder portions to define allochiral indentations in said handle member, said second terminal portion having a limb receiving slot opening endwise of said handle member.
